UNITED STATES PATENT OFFICE

2,571,652

STRAW GATHERER AND CHOPPER

Lloyd A. Bass, Crawford, Nebr.

Application June 27, 1947, Serial No. 757,635

3 Claims. (Cl. 55—118)

1

This invention appertains to novel and useful improvements in devices for conditioning straw and other flora for the purpose of easily and conveniently applying the same to agricultural areas.

An object of this invention is to provide a frame adapted to be secured to a prime mover, a housing secured to said frame and means for raising and lowering the housing relative to the ground as a datum.

Another object of this invention is to provide means, ancillary to wheel means, for skiddingly engaging the ground thereby assisting in supporting the said housing.

Another purpose of the present invention is to provide means for selectively adjusting the skid means relative to the said housing.

A further purpose of this invention is to provide improved straw pick up means and improved means for separating the straw from said pick up means.

A further purpose of the present invention is to provide, in addition to said straw pick up means, means for cutting any straw which is standing and means for conveying all of said straw to a selected, predetermined position within said housing.

A still further purpose of this invention is to provide fracturing means adjacent said conveyor means for twisting, bending and otherwise distorting straw prior to the admission of the same in means for crushing the straw.

Another object of this invention is to provide cutter means adjacent said fracturing means for the obvious purpose of slicing and otherwise cutting the straw.

Another purpose of this invention is to provide means for directing the conditioned straw from the housing to selected areas of the ground.

Another purpose of the present invention is to provide resilient means for adjusting the cutter means thereby automatically retaining the same in the selected, operative cutting position.

Another purpose of the invention is to provide extension means on said urging means for effectively lengthening and/or shortening the throw of the same.

Ancillary objects and features of novelty shall become apparent to those skilled in the art, in following the description of the preferred embodiment of the present invention, illustrated in the accompanying drawings, wherein:

Figure 1 is an elevational side view of the preferred form of the present invention;

Figure 2 is a plan view of the invention dis-

2

closed in Figure 1, portions broken away to illustrate details of construction;

Figure 3 is an elevational side view of the present invention, portions being removed for clarity;

Figure 4 is a longitudinal sectional view of the invention disclosed in Figure 2, taken substantially on the line 4—4 thereof and in the direction of the arrows;

10 Figure 5 is an elevational side view of the present invention, portions being shown in section to illustrate details of construction;

Figure 6 is a transverse sectional view of the invention disclosed in Figure 4 and taken substantially on the line 6—6 thereof and in the direction of the arrows;

Figure 7 is a transverse sectional view of the detail of construction shown in Figure 6, taken substantially on the line 7—7 thereof and in the direction of the arrows;

Figure 8 is an enlarged sectional detail of construction taken substantially on the line 8—8 of Figure 5 and in the direction of the arrows;

25 Figure 9 is an elevational fragmentary detail of construction showing particularly the straw urging means forming part of the present invention;

Figure 10 is a transverse sectional view of the detail of construction shown in Figure 9 and taken substantially on the line 10—10 thereof and in the direction of the arrows;

Figure 11 is an enlarged sectional detail of construction taken substantially on the line 11—11 of Figure 2 and in the direction of the arrows, and;

35 Figure 12 is a sectional view taken substantially on the line 12—12 of Figure 1 and in the direction of the arrows, illustrating particularly the clutch means used in conjunction with the present invention.

40 This invention has been conceived and developed to provide a device for conditioning flora which is normally in a growing position and in a position adjacent the ground. It is within the purview and one of the prime purposes of the present invention to not only pick up and condition growing positioned flora, but also to raise and utilize the flora which is lying on the ground.

50 It is believed that an understanding of the present invention will become readily apparent from the description of the general operation of the invention and accordingly, the same will be set forth before going into the structural detail of the invention. A frame is provided and is

55

adapted to be secured to a suitable prime mover such as a tractor or any suitable equivalent. Then, a housing is associated with the said frame and means are provided for selectively raising and lowering the housing in order to adjust the distance between the bottom of the said housing and the grade line. This adjustment obviously regulates the depth to which the invention may operate. An aperture is provided in the under-surface of the said housing and means is journaled therein for picking up straw or the like which is in a prone position. The details of this means for picking up the straw forms an important part of the present invention and will be discussed in detail hereinafter. Then, the straw which was picked up is mechanically removed from the pick up means and conveyed longitudinally of the housing. At a position adjacent the terminal portion of the means which is used for conveying, there is provided a cutter means for the purpose of trimming straw which is in a growing position. This cutter means may be a conventional sickle bar arrangement if so desired.

At this point, in the cycle of operation, there is introduced means for urging all of the straw through a common conveyor means which leads the same to a specially provided fracturing device. This fracturing device is rotatably journaled in the said housing and is provided for the purpose of bending, twisting and otherwise manipulating the straw and also for the purpose of leading the same and urging the same toward a pair of crushing rollers. These rollers squeeze the straw and eject the same to a position whereby efficacious cutting may take place. Of course, cutter means is provided for this purpose and then, the completely treated straw or other flora, is ejected through an exit means. Upon discharge of the treated straw, the same may be spread over a predetermined area of ground to be conditioned for agricultural purposes. Of course, it is within the purview of the present invention to provide receptacle means adjacent the said discharge means for the purpose of gathering and retaining the treated straw.

The above brief description of the method of operation, or more specifically, the method of conditioning straw, sets forth the general principles of operation.

The specific details of construction will be treated at this time. A frame 10 is provided of a plurality of truss members, tie rods and other structural elements, the actual number of truss members being left to the discretion of sound engineering principles. Any suitable, conventional hitch 14 may be provided at the rear portion of the truss members or frame 10. Obviously, the hitch is to be utilized in connecting the said frame 10 to a suitable prime mover. An axle 12 is suitably journaled in the said frame 10 and conventional wheels 16 are provided at the opposite ends thereof. A housing, generally indicated at 18, is provided with brackets 20 depending therefrom. These brackets terminate in conventional split bearings 22 which embrace the said axle 12. By this construction, it may be readily appreciated that the said housing 18 is pivotally journaled to the said axle 12 thereby associated with the said frame 10.

Taking the elements which form the major portion of the present invention in the order in which they are utilized for conditioning straw or other flora, reference is made first to the means provided for picking up and separating

straw which is in a prone position relative to the ground.

For the best understanding of this portion of the invention, attention is directed to Figures 4, 5 and 7. A shaft 24 is rotatably journaled transversely of the housing 18 and is positioned partially within a suitable aperture provided at the under portion thereof. A plurality of collars 26 are secured at stations along the longitudinal axis of the said shaft 24 and extensions 28 project therefrom. A plurality of cylindrical baffles 30 is interposed between the said extensions 28 and the baffles are eccentrically positioned relative to the said shaft 24. In securing the baffles in a relatively fixed position, use is made of a tie bar 32 which extends parallel to the longitudinal axis of the shafts 24. This tie bar 32 may be anchored to the sides of the said housing 18 by any suitable, conventional means. It will be noted from an inspection of Figure 7 that the said baffle cylinders 30 are so positioned as to strip any straw from the extensions 28 at a certain selected portion of the travel thereof. It will be noted from a close inspection of Figure 7 that conventional keyways and keys 34 may be employed for retaining the said collars 26 in an immovable fixed position relative to the shaft 24. It is also apparent from an inspection of Figure 6 that suitable thrust bearings 36 may be employed wherever found desirous in the system. Also, slots 38 are utilized as journaling positions within said housing 18, for a purpose to be subsequently set forth.

Taking now the means for driving or actuating the said straw pick up means, reference is made to Figure 2. Here, it is seen that a shaft 40 is provided in the said frame 10 and a universal joint 42 connects a second shaft 44 thereto. A hollow shaft 46 forms a continuation of the said shaft 44 and a slip clutch, generally indicated at 48 is then interposed in the system. This slip clutch is conventional in nature, consisting of a collar 50 which may be detachably secured to the said hollow shaft 46 by utility of screws 52. A drive shaft 54 is received in the bore of the said hollow shaft 46 and a second collar 56 is secured thereto. Now, both collars 50 and 56 are provided with gear seats 58 adapted to be in mesh. Means for resiliently biasing the said collar 56 is provided. It is noted at this point that the last mentioned collar 56 is slidably received on the shaft 54 and that the resilient biasing means is preferably a coil spring 60 interposed between said collar 56 and a relatively stationary thrust bearing 62. This thrust bearing is received on the said shaft 54 as is clearly evident from an inspection of Figure 11. It is seen that the drive shaft 54 terminates in a second universal joint 64 which has a torque tube 66 extending therefrom. This torque tube is received in a gear box transmission means 68 which has an axle housing 70 extending therefrom. Torque is transmitted from the prime mover through the various gears, clutches, universal joints and other mechanisms to a pulley 72 which is received at the terminal portion of the said shaft 24. The specific means for transmitting this torque will be described in more detail in the subsequent portion of the specification. However, for the present, it will be noted that the shaft 24 is preferably belt driven and it is for this reason that the said shaft 24 is journaled in the said slot 38. Obviously, adjustment may be effected within said slots.

Taking now the second means for treating the

said straw, there is disclosed in Figure 4 an endless conveyor means or belt 74 journaled on suitable rollers 76. These rollers have shafts 78 extending therethrough which are, in turn, journaled in the sides of the said housing 18. On the outer sides of the said housing 18 there is provided pulleys for the purpose of actuating the said endless conveyor belt means. Any suitable type of conveyor belt may be utilized.

As is well known to those skilled in the agricultural profession, often an appreciable amount of hay or straw is left standing and a device for picking the said straw up is relatively inefficient when used in conjunction with the standing straw. Accordingly, a sickle bar cutting means is provided adjacent the rear portion of the aperture on the underside of the said housing 18. The sickle bar construction may be viewed in Figure 8 wherein there is disclosed a pair of brackets 80 and 82 respectively extending from the said housing 18. Bearings 84 are provided at the terminal portions of the said brackets 80 and 82 respectively and a shaft 86 is journaled therein. This shaft is provided with a plate 88 at one end thereof with a ball socket eccentrically secured thereon. The usual sickle-bar pitman 90 is secured to said ball socket and to another suitable ball socket on a sickle bar 92. This sickle bar 92 is reciprocatably carried in a bracket 94 which is detachably secured to the bottom portion of the said housing 18. Conventional screws may be utilized in this securing operation. Slots 96 are provided in the said bracket 94 and lugs 98 extend from said sickle bar within the said slots 96. Teeth 100 project from the said sickle bar 92 for the purpose of not only cutting but also guiding the standing straw. Of course, the usual stationary guide members 102 are positioned above the cutting teeth of the said sickle bar and cooperate therewith for cutting purposes.

After the cut straw is felled, the same is then conveyed for the second conditioning operation as follows: An endless conveyor belt 104 is journaled within the said housing 18 and is received around rollers 106 which are similar to the said rollers 76. Of course, suitable shafts 108 extend through said rollers for journaling the same in the housing 18.

Common means for urging all of the straw treated hereinabove is provided. This common means consists of a triangular shape rotating member or reel which is journaled on a suitable shaft 110 within the said housing 18. Substantially U-shaped extensions 112 are received at the apex portions of the said triangular-like straw urging means and suitable slots are provided therein. These slots 116 have suitable securing means such as bolt and nut constructions 118 extending therethrough. Of course, a suitable slot 120 is also received in the said triangular shaped member for also receiving the bolt and nut construction therethrough. This urging means is positioned between the endless conveyor belts 74 and 104 respectively, thereby operating on all of the straw which has been cut.

The stationary baffle bar 122 extends transversely of the said housing 18. This transverse baffle bar is positioned adjacent the forward-most portion of the said endless conveyor belt 104. This baffle bar 122 is also provided for the purpose of cooperation with a fracturing means 124 which is also journaled in the said housing. This fracturing means consists of a cylindrical

member having protuberances 126 extending about the periphery thereof. Also, a suitable shaft 128 extends through said cylindrical member which is actually journaled in the said housing 18.

Then, it will be noted from an inspection of Figure 4 that a pair of rollers 130 and 132 are provided for receiving the straw from the endless conveyor means 104 and for crushing the same. Going now to Figure 3, it will be noted that the shaft 138 on which the roller 130 is journaled is received in a cage 136. A spring 139 is interposed between a bearing member, in which the said shaft is journaled and an upper bearing 140 which is adjustably received in the said cage 136. A conventional wing nut and screw construction 142 may be utilized for selectively compressing or decompressing the spring 144. Of course, through this medium the idler roller 130 may be adjusted as to pressure exerted therebetween and between the said roller 132.

After the straw is crushed the said rollers conduct the same to a cutting means positioned adjacent the rearwardmost portion of the housing 18. This cutter means is preferably a rotatable member 146 rigidly secured to a shaft 148. The said shaft 148 terminates in the housing 18 and a plurality of arcuately curved blades 150 are conventionally secured thereto. A cutter bar of the stationary type 152 is secured adjacent the outermost portion of each of the said cutter blades 150 while the same are in rotation. Of course, this shears the straw and also, through the medium of the curvature of the blades 150, the cut straw is urged through the discharge aperture 154.

Going now to the specific means for driving and controlling the above mentioned and described operating elements, reference is first made to means for pivotally adjusting the housing 18 about the said shaft 12 as an axis. A quadrant 155 is secured to the said frame 10 and a conventional locking means 158 is pivoted to the said frame 10. A pawl 160 is also pivoted to said locking means for engagement with the slots in the quadrant 156. An actuating rod 162 is pivoted to a selected length of the said locking means and an extension 164 is adjustably secured thereto through the medium of a pin-aperture construction. A bell crank 166 is pivoted to the said frame 10 and a terminal portion thereof is pivotally secured to the extension 164. The opposite end of the bell crank 166 has a roller bearing 168 secured thereto which engages a chain means 170. This chain means is secured to a suitable bracket 172 on the said housing 18 and to a spring means 174. The said spring means has a rod 176 secured to the opposite end thereof which extends through a housing 178. Now, this housing 178 is rigidly secured to the said frame 10 and the rod 176 terminates in an anchoring means or bracket 180. It may be readily appreciated that upon actuation of the said bell crank through the medium of the locking means, the slack in the chain means 170 may be selectively taken up and relaxed thereby resiliently lifting the housing 18 about the axle 12 as an axis. This, of course, regulates and compensates for varied, desired heights of the cutting elements described above, relative to the ground or grading line as a datum.

In order to assist in supporting the said housing 18, skid means is provided. This skid means consists of brackets 182 secured to the said hous-

ing 18 which terminates in longitudinal skids 184. Apertures are received in the member 182 and conventional detachable bolts with wing nuts 186 are secured therethrough. By utility of this construction, the skids 184 may be adjusted to also regulate the height of the cutting means and pick up means from the grade line.

A pulley 188 which is, in effect, a double sheave is secured to the shaft 190 in the said axle housing 70, described above. A belt, preferably a V-grooved belt, 192 is received around the said pulley 188 and also around a pulley 194 which is rigidly secured to the said shaft 148. As mentioned above, this shaft 148 has the rotatable member 146 rotatably secured thereto. A second V-grooved belt 194 is also received around the double sheave 188 and around a pulley 196, which is rigidly secured to the shaft extending through the roller 132. As also mentioned above, this roller 132 is the power roller operatively associated with the idler roller 130. A bevel gear 198 is secured to the terminal portion of the shaft associated with the said roller 132 and a second bevel gear 200 is meshed therewith. Brackets 202 terminating in bearings 84 are secured to the side of the said housing 18 and a shaft 204 is journaled therein. It is upon this shaft that the said bevel gear 200 is rigidly secured and a universal joint 206 is received on the opposite end of the said shaft 204. This universal joint has the above described shaft 86 secured thereto which is utilized in actuating the eccentric plate 88 for reciprocation of the sickle bar cutter means.

Sprockets 210 and 212 respectively are secured to the terminal portions of the shafts 128 and 108 respectively. As discussed above, the shafts are operatively associated with the fracturing means 124 and a selected roller 106 of the said endless conveyor means. This is a portion of the driving mechanism utilized in conjunction with the present invention. For the remainder of the drive mechanism, reference is made particularly to Figure 1.

Here it is seen that the shaft 130 is provided with a sprocket at the opposite end thereof, the sprocket being indicated by the numeral 214, and a chain means 216 extends therearound. At this point it is noted that a chain means 218, similar to the chain means 216 extends around the sprockets 212 and 210. As is well known in the art, these chains are conventional in nature, being operatively associated with conventional sprockets.

The said chain 214 is also received on a sprocket 220 which is rigidly secured to the shaft 148. An idler gear 222 may be received in the chain system at this point for the purpose of adjusting the tension thereof. A cage 224 is secured to the side of the housing 18 and a spring received therein. The conventional bearing-adjustable bolt and wing nut construction may be utilized herewith as described above.

Sprockets are also received on the opposite terminal portions of the shaft 108 and shaft 224 which are received in the roller 132. A chain 226 is also received therearound in this transmission system. An idler gear 228 is received in the side of the said housing 18 and a conventional chain means 230 extends therearound and around another gear 232 fixed to the main axle within the housing 12. A relatively large belt 234 extends around a pulley 236 which is secured to the shaft 224. This belt also extends around a pulley 238 which is fixed to the shaft 78 then around a

pulley 240, fixed to the shaft 24. The said belt 234 then continues to engage a pulley 242 which is fixed to the shaft 244. This shaft 244 has an arm 246 extending therefrom which is pivoted to the housing 18. A bracket 248 is positioned below the said arm 246 and screw means 250 is threadingly received in the said bracket 248, engaging a selected undersurface of the bracket 246. Obviously, this device may be utilized for adjusting, lengthening and shortening the efficacy of the belt 234. By utility of the above described belt arrangement, the straw cutter elements are driven. Then, as is seen in Figure 1, another belt 252 extends around a pulley 254 which is rigidly secured to the shaft 108. The said shaft 108 is obviously secured to the roller 106 which forms a portion of the endless conveyor means described hereinbefore. The said belt 252 derives its power from the chain driven idler gear 228 which has a pulley 256 fixed immovably on the back thereof or if desired, fixed immovably to the shaft 258 on which the said idler gear 228 is attached.

A clutch mechanism is supplied on the end of the shaft of the idler roller. When the invention is moving forward, there will be times when the same picks up large amounts of straw. Too much straw might be received within the housing 18 so that the cutter means would be rendered inefficient. Accordingly, with the addition of a clutch assembly (see Fig. 12) for use in association with the idler roller, the amount of straw which is compressed between said rollers 130 and 132 may be regulated thereby regulating the amount of straw which is introduced to the cutter means. This clutch is in the form of an automatic device whereby upon too much separation of the rollers 130 and 132, the lower or drive roller is disengaged from the usual drive. A sleeve member 260 is slidably received on the shaft 108 and it is on this sleeve member that the gear 214 is placed. A friction plate 262 is secured to said sleeve 260 and a second friction plate 264 is secured to a second slidable sleeve member 266 which is slidably splined on the shaft 108. The bracket 268 is secured to a selected portion of the housing 18 and a bell crank 270 is pivoted thereto. In this portion of the invention, a bearing block 272 is supplied with the usual spring 144 and adjusting means 142. It will be noted that the bearing block 272 is somewhat different from the lower portion member 139 in that an arm 274 extends therefrom. A slot is provided in the said extension arm 274 and an adjustable nut and bolt construction is received therein. The opposite end of the said nut and bolt construction terminates in a pivot means which is secured to a selected end of the bell crank 270. A spring 276 is biased against a suitable thrust bearing 278 which is rigidly attached to the shaft 108 and also biased against the slidtable collar or sleeve 266. By this construction, it may be readily appreciated that upon lifting of the pressure roller 130 the clutch members formed by the plates 262 and 264 may be selectively engaged and disengaged.

While there has been described and illustrated but a single preferred embodiment of the present invention, capable of performing all of the specifically mentioned objects, as well as other objects, it is apparent to those skilled in the art that various changes including omissions and additions may be made herein without departing from the spirit of the invention. Accord-

ingly, limitation is sought only in accordance with the scope of the following claims.

Having described the invention, what is claimed as new is:

1. A straw cutter comprising an axle assembly with wheels mounted at opposite ends thereof, a frame connected to said assembly and adapted to be drawn by a tractor, a housing, means secured at one end of said housing pivotally attaching said housing to said assembly, a skid for said housing secured to the housing at the opposite end thereof, said housing having a field straw inlet opening, means disposed in said opening and carried by the housing for picking up fallen straw, a straw fracturing device secured to and within said housing adjacent its end opposite said inlet opening, means journaled within said housing for conveying picked up fallen straw to said fracturing means, a cutter for standing straw and carried by said housing behind said fallen straw pick up means and disposed in said opening, means for conveying cut straw into said fracturing device, and a reel journaled in said housing between said fallen straw conveying means and said cut straw conveying means.

2. A straw cutter comprising an axle assembly with wheels mounted at opposite ends thereof, a frame connected to said assembly and adapted to be drawn by a tractor, a housing, means secured at one end of said housing pivotally attaching said housing to said assembly, a skid for said housing secured to the housing at the opposite end thereof, said housing having a field straw inlet opening, means disposed in said opening and carried by the housing for picking up fallen straw, a straw fracturing device secured to and within said housing adjacent its end op-

posite said inlet opening, means journaled within said housing for conveying picked up fallen straw to said fracturing means, a cutter for standing straw and carried by said housing behind said fallen straw pick up means and disposed in said opening, means for conveying cut straw into said fracturing device, a reel journaled in said housing between said fallen straw conveying means and said cut straw conveying means, and said housing having a fractured straw outlet therein located rearwardly of said fracturing device.

3. The combination of claim 1 and means connected to said housing and frame for pivotally lifting said housing, and means yieldingly holding said housing in a selected pivoted position.
